(57) CLAIM

The ornamental design for a disposable plastic liner for a bucket, as shown and described.

DESCRIPTION

FIG. 1 is a perspective view of a disposable plastic liner positioned in a bucket showing my new design;

FIG. 2 is a perspective view of the disposable plastic liner removed from the bucket;

FIG. 3 is a top plan view of FIG. 2;

FIG. 4 is a bottom plane view thereof; and,

FIG. 5 is a front elevational view thereof, wherein the rear elevational view as well as the left and right side elevational views is a mirror image of the front elevational view.

The bucket shown in broken lines is for illustrative purposes only and is hereby disclaimed as forming no part of Applicant's claimed invention.
